UNITED STATES PATENT OFFICE.

ALBERT CHAMPION, OF FLINT, MICHIGAN, ASSIGNOR TO A C SPARK PLUG COMPANY, OF FLINT, MICHIGAN.

INSTRUMENT ASSEMBLY.

Application filed February 17, 1926. Serial No. 88,967.

This invention relates to instrument assemblies of the type in which several instruments are mounted on a suitable plate which is then secured upon the instrument board, 5 but it is of equal utility for the mounting of a single instrument or for use where the mounting plate forms an integral part of the instrument board.

In this type of assembly it has heretofore 10 been proposed to provide a mounting plate with brackets for supporting an instrument, and to conceal the rivets or bolts which secure the brackets to the plate by means of a face plate overlying the mounting plate and 15 secured thereto. Such a construction is disclosed in the application of Frank Nutt, Ser. No. 89,366, filed February 19, 1926. In this application the plates have been provided with alined apertures for receiving a projecting 20 portion of the instrument bezel, the bezel being provided with a flange which engages the rear face of the mounting plate. As the face plate and the mounting plate are spaced some distance apart this construction 25 has necessitated the use of a special or supplemental bezel having the part which projects through the alined apertures of greater than standard in order that the outer portion of the bezel may be properly displayed at the 30 face of the panel.

My invention consists in so modifying the construction disclosed and claimed in the Nutt application that instruments having standard bezels may be employed. This I 35 have accomplished by making the aperture in the mounting plate larger than the aperture in the face plate, thus permitting the bezel to pass entirely through the mounting plate so that the shoulder of the bezel engages 40 the rear face of the face plate. This construction also possesses the advantage that the instrument is supported in proper position with a slight degree of resiliency.

Referring to the drawings:

Figure 1 is a front elevation of my improved instrument assembly.

Figure 2 is a section on line 2-2 of Figure 1.

The usual automobile instrument board is indicated by the reference character 2. The board is apertured as at 4 to receive plate 6 upon which the instruments are mounted. As the instruments are supported in identical fashion I have preferred to show only the 55 mounting for the speedometer 8. Thus I

have provided a U-shaped bracket member 10 secured to plate 6 by suitable fastening devices such as screw bolts 12. To this bracket the speedometer is clamped by means of studs 13 projecting from the instrument casing and 60 extending through apertures in the supporting bracket and carrying suitable nuts for clamping the instrument in position. The speedometer is provided with the usual bezel 14 formed with shoulder portion 16. This 65 bezel extends through aperture 18 in the supporting or mounting plate 6 and a portion thereof extends through aperture 19 in face plate 20, the shoulder portion 16 of the bezel 70 engaging the rear face of the face plate. This 75 plate is secured to the mounting plate 6 in any suitable manner, as by bent over tongues 22 passing through slots 24 provided in the mounting plate.

This construction permits the use of a 75 bezel of standard length for there is nothing but face plate 20 which consists of rather light stock, overlying the shoulder portion 16 of the bezel. At the same time the instrument is yieldingly supported and centered by the face plate.

It is apparent that this invention is of equal utility where the supporting plate 6 forms an integral part of the instrument board. This method of mounting may be 85 used with any type of instrument or dash fitting and without the use of special bezels or housings. It is easy to assemble and the plate 20, which may be provided with any suitable color or character of finish, affords 90 an opportunity to secure many pleasing ornamental effects. The construction is also of such character that no alteration in the design of instrument housings is necessary.

I claim:

1. An instrument assembly comprising a supporting plate having an aperture therein, an instrument, means for securing the instrument to the supporting plate with a portion thereof projecting forwardly thru the aperture, said aperture being of a size to permit rearward withdrawal of the instrument, a face plate overlying the supporting plate and in spaced relation thereto and concealing said securing means, said face plate being provided with an aperture in which the said forwardly projecting portion of the instrument is snugly received.

2. In the combination as defined in claim 1, said supporting plate being provided with 110

a peripheral flanged portion within which said face plate is received.

3. The combination of a supporting plate having an aperture therein, an instrument loosely fitted in said aperture, means for securing the instrument to the supporting plate, and a face plate overlying said sup-

porting plate and secured thereto in spaced relation and having an aperture in which said instrument is snugly fitted to hold it in adjusted position. ¹⁰

In testimony whereof I affix my signature.

ALBERT CHAMPION.
